UNITED STATES PATENT OFFICE.

BERNARD P. FALTIN, OF BAREVILLE, PENNSYLVANIA.

DISPENSING-PUMP.

1,394,191.

Specification of Letters Patent.

Patented Oct. 18, 1921.

Application filed October 27, 1919. Serial No. 333,449.

To all whom it may concern:

Be it known that I, BERNARD P. FALTIN, a citizen of the United States, residing at Bareville, in the county of Lancaster and 5 State of Pennsylvania, have invented certain new and useful Improvements in Dispensing-Pumps; and I do hereby declare the following to be a full, clear, and exact description of the invention, such as will enable others skilled in the art to which it 10 appertains, to make and use the same.

This invention relates to housings and doors for inclosing dispensing pumps.

An object of this invention is to provide 15 a housing and door that may be quickly and easily opened and adapted at the same time for protecting the usual form of gasoline dispensing pump.

A further object of this invention is to 20 provide an improved housing and door for dispensing pumps in general.

A further object of this invention is to provide a suspended door mechanism for dispensing pumps, and easy means of operating 25 said door and improved and simplified bearings for doors in housings of said pumps.

Considerable difficulty has been occasioned 30 in making pumps of this character and providing accessible housings therefor in that it has been considered quite essential that the dome be of greater diameter than the pipes beneath it in order to properly shed the water, and that the pedestal be the least 35 in diameter, and that the section between the dome and the pedestal, if inserted, be of lesser diameter than the dome and of greater diameter than the pedestal.

An object of this invention has been to 40 provide a weatherproof dome of symmetrical and uniform structure and to overcome such difficulties.

With these and other objects in view the invention consists of the construction, the 45 combination, the detail, and arrangements of parts as hereinafter more fully described and claimed.

In the drawings:

Figure 1 is a side elevation of the usual 50 dispensing pump to which this invention relates showing that which does not relate to this invention in skeleton.

Fig. 2 is an enlarged fragmentary side elevation.

Fig. 3 is a section at 3—3 in Fig. 2 showing the door closed. 55

Fig. 4 is a fragmentary enlarged section of one of the lower rollers and its corresponding parts.

Fig. 5 is a fragmentary section showing 60 the door suspension bearing taken at 5—5 in Fig. 6.

Fig. 6 is a like view to Fig. 3 showing the door open.

In detail the invention comprises a semi-tubular door A and a semi-tubular complementary housing B, and means for mounting the same as hereinafter described. 65

In the usual type of housing for gasoline dispensing pumps the housing comprises a 70 base member 2, having a dome 3, which is elevated in order to uncover the base portion 2 and which is usually provided with counterweights to make easier the counterweighting of this dome. 75

In this device it is unnecessary to provide for the flexing of connections and such between the dome and the base. It also obviates the using of counterweights and the like for counterbalancing the weight of 80 this dome, and provides a much more desirable means of access to the said pump. Thus, when it is desired to use this invention in a device already constructed having the elevating means in common use for opening 85 the housing, all that is necessary to install it is to affix a stud mount 4 by brackets 5 to the dome of the housing and rotatably mount the door A by a stud 6 to said mount 4 by inserting said stud in said mount and 90 locking the same with a nut 7. Door A is provided with a top 8 having a hub 9, which hub 9 is bored to mate stud 6 and is held in upright position by shoulder 10 upon said stud 6. Thus, the whole door is held in 95 suspension upon stud 6. A means of guiding said door and keeping the same in alignment relative to its mount on stud 6 is provided by rollers 11, which rollers 11 have a clearance so that none of the weight rests 100 upon them but they rest laterally against the usual annular portion 12 of such housings. Rollers 11 are mounted upon the door A by a stud 13 which is riveted into the said door in a countersunk recess at 14. In the 105 door A is an inward curl 15 and in the casting B is an outward curl 16 suitably overlapping the space as provided between the

door A and the casing B as shown adjacent to curls 15 and 16. In construction, owing to the fact that the usual housing is an annulus such as 12 with a recessed portion 5 17 for receiving the dome, all that is necessary is to raise the dome of the said tank and affix the brackets 5 and affix the casing B with screws 18 to the annulus 12 and the dome 3, and thus the door and casing are 10 completely installed.

Obviously where this invention is not being adapted to old construction and where it is desired to have the advantage of a door of this type, much of the interior mechanism 15 of the old style of housing can be dispensed with, such as the counterweights and springs for elevating the dome and the provision for flexing and longitudinal motion of the dome relative to its component parts.

20 A lock is provided at 19 with a key socket 20 to hold the said door in locked relation as desired when closed.

In operation all that is necessary is to engage with the hand a handle 20 and swing 25 the door in angular relation after it has previously been unlocked and the interior of the housing is exposed, thus affording convenient access for operating said pump.

It is obvious that a door of this type possesses among many other advantages in relation to its easy operation also the advantage of taking less space than like doors having a vertical axis.

It is further obvious that the pump here illustrated is of symmetrical structure and 35 substantially uniform in diameter throughout and that at the same time it is weather-proof.

Claim:

In a housing for a dispensing device, a 40 pedestal having a circular guide rim formed with a rabbet on its outer and upper edge, a cylindrical casing having a fixed part and a rotatable part, the lower edge of the fixed part being secured to the outer face of the 45 guide rim, the rotatable part being pivotally secured from above and its lower edge slidably seated in the rabbet on the circular guide, and a plurality of grooved rollers 50 secured to the inner face of the rotatable part adjacent its lower edge, the grooves of the rollers seating over the upper edge of this circular guide to secure the rotatable part thereon.

In testimony whereof I affix my signature. 55

BERNARD P. FALTIN.
